CLAIM

The ornamental design for a motor vehicle as shown and described.

DESCRIPTION

FIG. 1 is a front and right side perspective view of a motor vehicle showing our new design;

FIG. 2 is a top, front and right side perspective view thereof;

FIG. 3 is a front view thereof;

FIG. 4 is a right side view thereof;

FIG. 5 is an enlarged view thereof, taken from area 5 in FIG. 1;

FIG. 6 is an enlarged view thereof, taken from area 6 in FIG. 4;

FIG. 7 is a front and left side perspective view thereof, shown enlarged for ease of illustration; and,

FIG. 8 is a bottom, front, right side perspective view thereof, shown enlarged for ease of illustration.

The claimed design is shown in full contrast that indicates claimed areas. The ghosted or low contrasted showing of the motor vehicle is provided for the purposes of illustrating environmental structure that forms no part of the claimed design. The dash-dash broken lines are included as boundary lines and form no part of the claimed design. The dash-dot broken lines indicating the boundaries of the enlarged views and the dash- dash broken lead lines, form no part of the claimed design.
